CLAIM

The ornamental design for a rim for tableware, as shown and described.

DESCRIPTION

FIG. 1 is a perspective view of a rim for tableware showing my new design;

FIG. 2 is a top plan view thereof, the broken line suggestion of a tableware forms no part of the present invention;

FIG. 3 is a front elevation view thereof, the rear elevation view being identical thereto, the broken line suggestion of the bowl forms no part of the present invention;

FIG. 4 is a left side elevation view thereof, the right side elevation view being identical thereto;

FIG. 5 is a perspective view of a second embodiment of the rim;

FIG. 6 is a top plan view thereof;

FIG. 7 is a front elevation thereof, and rear elevation view being identical thereto; and,

FIG. 8 is a left side elevation view thereof, a right side elevation view being identical thereto.
